UNITED STATES PATENT OFFICE.

EDMUND E. BECHTOLD, OF CHICAGO, ILLINOIS.

INSULATION.

SPECIFICATION forming part of Letters Patent No. 758,165, dated April 26, 1904.

Application filed June 22, 1903. Serial No. 162,470. (No model.)

To all whom it may concern:

Be it known that I, EDMUND E. BECHTOLD, a citizen of the United States, residing at Chicago, in the county of Cook and State of Illinois, have invented certain new and useful Improvements in Insulation, of which the following is a specification.

This invention relates to improvements in insulation, and while it is more especially intended to be used for insulating canopies, such as are employed for electric-light fixtures or combination fixtures, from the walls or ceilings of rooms or other supports, yet it is applicable for insulating other pieces or devices; and it consists in certain peculiarities of the construction, novel arrangement, and operation of the parts thereof, as will be hereinafter more fully set forth and specifically claimed.

One of the objects of the invention is to provide insulation which may be carried in stock ready to be applied to the canopy or other article, so as to effectually insulate it from its support.

Another object is to so construct the canopy or other article to be insulated that the insulating material may be applied thereto or secured in place thereon without the use of brads or rivets.

A further object is to so construct the insulation when designed to be used as stock that it can be attached to the canopy or other device without the use of brads or rivets.

Other objects and advantages of the invention will be disclosed in the subjoined description and explanation.

In order to enable others skilled in the art to which my invention pertains to make and use the same, I will now proceed to describe it, referring to the accompanying drawings, in which—

Figure 1 is a view in side elevation of a portion of the wall of a building, showing a canopy secured thereto and insulated therefrom by means of insulation embodying my invention. Fig. 2 is an inner view, partly in section, of a portion of the insulating stock, showing it ready to be applied to or secured on the rim of a canopy or edge of another device. Fig. 3 is a cross-sectional view of the insula-

tion and a portion of the canopy, showing the manner of securing the two together. Fig. 4 is a face view of a blank comprising a part of the insulation. Fig. 5 is an inner perspective view of a portion of the canopy, showing a modification in the construction of the insulation. Fig. 6 is a fragmental face view of a portion of the blank comprising a part of the modified form of the insulation, and Fig. 7 is an inner fragmental perspective view showing another modification.

Like numerals of reference refer to corresponding parts throughout the different views of the drawings.

The reference-numeral 10 represents the canopy, which is mounted on the fixture 11 so as to cover its juncture with the wall, pipe, or wires and which it is desirable to insulate from the wall 12 or other support in order to prevent the current becoming grounded on account of the moisture in the wall or support or by reason of its electric conductivity.

In Figs. 2, 3, and 4 of the drawings I have shown one form of my insulation, which comprises a strip of metal 13, which has in one of its edges a series of slots 14, extending transversely therein to near its longitudinal center. The outer ends of the slots 14 are open, as shown, and have between them a series of openings 15, which when the metal is bent will register with a series of openings 16, arranged in a longitudinal line near the middle of the strip 13, as is clearly shown in Fig. 4 of the drawings. The strip 13 is bent to form substantially an S-shaped piece in cross-section—that is, it is bent longitudinally on a line at or near the inner ends of the slots 14, so as to form an inner portion 17, in which the opening 15 and slots 14 appear, and is then bent in the reverse direction to form an outer portion 18, between which and the intermediate portion or part 19 is located a strip of fiber 20 or other suitable insulating material.

When the strip 13 is thus formed into a compound bend or S-shaped piece, it is evident that the portions 17, 18, and 19 will lie approximately parallel with one another and that the openings 15 will register with the openings 16, so that when the rim or edge of the canopy 10 is placed between the inner

portion 17 and the intermediate part 19 it may be formed with indentations or projections 21 extending into the openings 16 and in engagement with the fiber or material 20, 5 so as to hold the latter securely in position. The indentations or projections 21 may be produced by means of an instrument placed in the openings 15, when by striking the instrument it is apparent that a portion of the 10 metal forming the canopy will be forced outwardly through each of the openings 16, so as to be embedded in or engage the insulating material or fiber.

In Figs. 5 and 6 I have shown a modification which consists in forming the canopy 10 or other device to be insulated near its rim or edge which will be located near the support with a compound or reverse bends, so as to produce substantially an S-shaped figure in 15 cross-section. In this modification the piece 10 is provided with a series of slots 22 and openings 23, arranged in a line near the inner ends of the slots and between the same, as shown. The material forming the device 10 20 is bent back upon itself at about the middle of the slots 22, so as to form an inner portion 24 and an intermediate portion 25, and is then bent in the reverse direction to form an outer portion 26, between which and the intermediate portion 25 is placed a strip of fiber 20 or other suitable insulating material, which is held in place by means of projections or indentations 27 on the intermediate portion 25, formed by an instrument inserted in the openings 23 in the inner portion. By reference 30 to Fig. 5 it will be seen that when the portion 10 is bent back upon itself on a line at about the middle of the slots 22 one half of each of said slots will be in the inner portion 24 and the other half in the intermediate portion 25 and will register with one another. By forming the strip 13 and material 10 with the slots 14 and 22, respectively, it is evident 40 that the material may be bent without buckling or crimping, so as to conform to the desired shape, and it is for this purpose that I employ said slots; but I do not desire to be limited to their use, as I may sometimes omit them.

50 In Fig. 7 I have shown another modification, which consists in employing the same construction as shown in Figs. 1 to 4, inclusive, and above described, except that the insulating material 20, which in this instance is 55 preferably of mica, is provided on its edge adjacent to the wall or support with a protecting strip or cap which is bent longitudinally to form reverse bends, so as to produce an inner portion 28, an outer portion 29, and 60 an intermediate portion 30, as shown.

The outer edge of the insulating material is located between the outer portion 29 and the intermediate part 30 and is held therein

by depressed portions of the intermediate part produced by an instrument inserted in the 65 openings 31 in the inner portion of the protecting-strip. The object of this strip is to strengthen the mica or other insulating materials.

Having thus fully described my invention, 70 what I claim as new, and desire to secure by Letters Patent, is—

1. As an improved article of manufacture, insulation comprising a piece bent to form an inner, an outer and an intermediate portion 75 substantially in parallelism, the inner portion being provided with transverse slots, and a piece of insulating material located between the outer and intermediate portions, the said intermediate portion being provided with projections to engage the insulating material, 80 substantially as described.

2. As an improved article of manufacture, insulation comprising a piece having a series of transverse slots and a number of openings 85 arranged in two longitudinal and parallel rows, the said piece being bent longitudinally to form an inner, an outer and an intermediate portion substantially parallel with one another, and so that one of the rows of openings 90 and the slots will be located in the inner portion and the other row of openings will be in the intermediate portion and will register with the first-named row, and insulating material located between the outer and intermediate portions, substantially as described.

3. As an improved article of manufacture, insulation comprising a piece bent to form an inner, an outer and an intermediate portion substantially parallel with one another, 100 the inner portion being provided with transverse slots, and a piece of insulating material located between the outer and intermediate portions, the intermediate portion being provided with means to engage the insulating 105 material, a protecting-strip located on the outer edge of the insulating material and comprising a piece bent to form an inner, an outer and an intermediate portion, the outer edge of the insulating material being located between the outer and intermediate portions of said strip and clamped thereby, substantially as described.

4. As an improved article of manufacture, insulation comprising a piece bent to form an 110 inner, an outer and an intermediate portion substantially parallel with one another, the inner portion having a series of slots and a number of openings located between the slots, a piece of insulating material located between 115 the outer and intermediate portions, substantially as described.

EDMUND E. BECHTOLD.
